COMPUTER INPUT-OUTPUT CONTROLLER FOR DIAGNOSTIC TESTING

Richard F. Snow, Southfield, and David A. Thomasson,
Northville, Mich., assignors to Ford Motor Company,
Dearborn, Mich.

Filed Aug. 6, 1973, Ser. No. 383,943

Term of patent 14 years

Int. Cl. D13—03

U.S. Cl. D26—13 C

FIG. 1

FIG. 2

FIG. 3

FIG. 4

FIG. 5

FIG. 6

FIG. 1 is a front view of a computer input-output controller for diagnostic testing according to our new design;

FIG. 2 is a rear view of the computer input-output controller for diagnostic testing;

FIG. 3 is a right-side view of the computer input-output controller for diagnostic testing;

FIG. 4 is a left-side view of the computer input-output controller for diagnostic testing;

FIG. 5 is a top view of the computer input-output controller for diagnostic testing; and

FIG. 6 is a bottom view of the computer input-output controller for diagnostic testing.

We claim:

The ornamental design for a computer input-output controller for diagnostic testing, substantially as shown.
